United States Patent Office.

EDWIN COWLES, OF CLEVELAND, OHIO.

Letters Patent No. 90,931, dated June 8, 1869.

IMPROVEMENT IN MACHINERY FOR CUTTING CARDS.

The Schedule referred to in these Letters Patent and making part of the same.

To all whom it may concern:

Be it known that I, EDWIN COWLES, of Cleveland, in the county of Cuyahoga, and State of Ohio, have invented certain new and useful Improvements on Card-Cutting Machinery; and I do hereby declare that the following is a full, clear, and exact description thereof, reference being had to the accompanying drawings, making part of this specification, in which—

Figure 1, sheet 1, is a perspective view of the machine.

Figure 2, sheet 2, is a top view, with a portion of the table-top broken away.

Figure 3, sheet 2, is an elevation of one side of fig. 2.

Figure 4, sheet 2, is a vertical cross-section through the self-discharging stiffener, showing the shears and one side of the chute behind it.

Figure 5, sheet 2, is an elevation of the feeding and guiding devices.

Figure 6, sheet 2, is a section through fig. 5 in the vertical plane indicated by line α .

Figure 7, sheet 2, is a sectional view, showing the expandible chute.

Similar letters of reference indicate corresponding parts in the several figures.

This invention relates to certain novel improvements on machinery which is designed for cutting cards of different sizes from the strips of card-board.

The strips are fed up to shears, and cut off in pieces of proper size, which pieces are received by a chute, and directed into proper receptacles.

The chute is adjustable for gauging the widths of the cards, and it is also made so as to allow the scraps to fall through it out of the way.

The card-strips are guided up to the work of cutting, and are held stiff while being cut, so that all the cards of a given required size will be uniform in shape.

The nature of my invention consists—

First, in a flanged-bottom inclined chute, which is provided with one adjustable side, so arranged as to serve as a gauge for the different widths of the cards required, and so constructed as to separate the cards from the scraps.

Secondly, in the employment, in combination with shears and a suitable feeding-device, of a self-adjusting stiffener, which will receive that portion of the strip which is to be cut off, and hold it by one edge during the act of cutting, then open and allow the card to be discharged, as will be hereinafter explained.

Thirdly, in self-yielding, adjustable guides, in combination with a stationary guide, a feeding-device, and shear-cutters, said yielding guides being adapted for holding one edge of the card-strip closely against the stationary guide, and thus properly directing this strip up to the shears.

Fourthly, in arranging a spring in such relation to the shears, on one side of a feeding-device, that the friction of the movable shear-blade against the edge of the card-strip, while this blade rises, shall not carry up with it or bend the strip, as will be hereinafter explained.

Fifthly, in a rotating frictional feed, in combination with card-cutting machinery, as will be hereinafter explained.

To enable others skilled in the art to understand my invention, I will describe its construction and operation.

In the accompanying drawings—

A represents a table-top, and B B, the legs thereof, which constitute a frame for supporting the card-cutting mechanism.

C is a driving-shaft, arranged in a horizontal plane, and having its end bearings in the legs B B of the table.

This shaft C carries, on one end, an eccentric or crank-plate, C¹, which communicates a vibratory motion to the shear-blade C³, by means of pitman C².

Shaft C also carries a grooved pulley, C⁶, that communicates rotary motion to a horizontal shaft, c, which is mounted on standards, d d, on top of the table, through the medium of a quarter-twist belt, c, and pulley c'.

The shear-blade C³ is pivoted to and operates in conjunction with a shear-blade, C⁴, which is secured to the edge of the table-top A, so that the cutting-edge of this blade is level, or nearly so, with the surface of the table-top, as shown in fig. 6.

Between the fixed shear-blade C⁴ and a horizontal cross-bar, G³, which is supported by extensions of the table-top, I arrange a chute, and also a self-discharging stiffener.

One side plate, G, of the chute, is secured fast to the edge of the table-top, just beneath and flush with the vertical surface of said blade, as shown in fig. 7.

The other side of the chute is secured fast to one end of a horizontal screw-shaft, G², which passes through a hole made through bar G³, and is connected to this bar by a feather and slot, so that while this shaft is allowed end-play, it is not allowed to turn.

This allows the plate G¹ to be adjusted nearer to or from the fixed plate G, and by means of the nuts k k, on said shaft G², and plate G¹, can be fixed rigidly at any desired point of adjustment.

The lower edges of the plates G G incline to one side, and are flanged at s s, to form guides and supports for the cards, but allow scraps to fall through or between the plates into a different receptacle from that into which the flanges s s conduct the perfect cards as they are cut.

The stiffener consists of two plates, F F', a separating-spring, o, (in fig. 4,) and an adjusting-screw, p.

The plate F is rigidly secured to one extension of

the table A, and the plate F' is hinged to plate F, and acted upon by spring o, for keeping the free end of the latter plate up in contact with the lower end of adjusting-screw.

The screw p is used for regulating the size of the space between the two plates, which space should be in the plane of the top surface of table A, so as to receive the side edge of the card-strip, and hold or stiffen the same during the cutting strokes of the shear-blade C³.

On that edge of the movable plate F', next the stationary blade C⁴, a lip, n, is formed, which is struck by the blade C³, just before or immediately after a card is cut from its strip, and thus the plate F' is depressed to allow a free discharge of the card in the chute.

When the blade C³ rises again, the plate F' is released, and its spring o allowed to throw it up against the screw p, to receive the card-strip again.

By thus holding the card-strip between plates, as above stated, the strip will be stiffened and kept flat and smooth while a card is being cut from it.

The upper portion of the chute-plate G¹ should rise a short distance above the horizontal plane of the table-top, for a reason hereinafter explained.

On the shaft c², a belt-wheel is fixed, and on opposite ends of this wheel, arms, E E, are loosely applied to this shaft c², which arms are connected together by a cross-bar, and are provided, on their free ends, with a small belt-wheel, r, the axis of which is parallel to the shaft c², as shown in figs. 2, 5, and 6.

Around these two wheels D r, a belt, D', is stretched, which I prefer to make of India rubber, but it may be made of any other suitable substance, which will afford the required friction.

From one side of the frame E, a stud extends, upon which presses a spring, m, fastened to an adjustable rod on standard d, which spring presses the free end of the frame E down upon the surface of table-top A with sufficient force to allow the belt D' to feed the strips of card-paper beneath it.

Beneath spring m is a fixed guide, e, arranged so as to receive against it one edge of a card-strip while feeding the same to the shears, and also so arranged as to direct a portion of the edge so guided between the two plates F F'.

On the opposite side of the frame E, to the fixed guide-plate e, are two perpendicular guides, f f, which are applied fast on the inner ends of horizontal rods, h h, that slide endwise in standards which rise from adjustable plates, g' g', that are connected together by bar g, as clearly shown in figs. 1, 2, and 5.

The springs i i, which are coiled around the rods h h, press the perpendicular guides f f toward the frame E.

The plates g' g' are adjustable toward or from the frame E, and the pins j j, which are inserted through holes made through side plates g' g', and into the table-top, are used to effect said adjustment.

Instead of the pins j j, set-screws, working through slots made through plates g' g', may be used.

The lower ends of the guides f f are recessed into the table-top to prevent the edge of a card-strip from working beneath these ends while it is being fed up to the work.

Operation.

The machine is adjusted for cards of different

lengths, by adjusting the plates g' g' and their guides f f nearer to or further from the fixed guide e, according to the width of the card-strips to be cut up; and the machine is adjusted for cards of different widths, by moving the chute-plate G¹ toward or from the shear-blade C⁴, for the width of the cards cut will be exactly equal to the distance between the said parts G¹ C⁴.

The shaft C being in motion, it will communicate vibratory motion to the shear-blade C³, and rotary motion to the belt D'. A card-strip is laid flat upon table-top A, and moved up by hand to the point of impingement of the belt D' upon the table-top. The strip is thus passed between yielding pressure-guides, f f, and fixed guide e, up to the shears.

The operator allows the end of the card-strip to pass a short distance beyond the cutting-edge of the shear-blade C³, and then holds the strip stationary till the shear C³ cuts off and squares the end, the scrap falling between the flanges s s, of chute-plates G G¹, and thus escaping out of the way. The card-strip is then released from the hand of the operator, and cut up into cards of the required width and of uniform width.

The feed-belt D' moves the card-strip along, till its end strikes the raised portion of the chute-plate G¹, when, if this belt will slip until a card is cut off, and the shear-blade C³ rises out of the way.

The operation of the stiffening-device has been fully described.

The spring t, which is secured to the guide f, nearest the shear-blade C³, is inclined so as to press upon and hold down the end or corner of the card-strip beneath it, and prevent it from being curled up by the movable blade C³ as this blade rises.

It is obvious that an India-rubber feed-cylinder, or a cylinder covered with rubber, or its equivalent frictional material, might be substituted for the feed belt D, although I prefer to use this belt.

Having described my invention,

What I claim as new, and desire to secure by Letters Patent, is—

1. An open-bottom chute, composed of a fixed plate, G, and an adjustable plate, G¹, flanged on their bottom edges, substantially as and for the purposes described.

2. The arrangement of the adjustable chute G¹, so as to serve also as a gauge-plate for regulating the widths of cards to be cut, substantially as described.

3. Stiffening-plates F F', in combination with a card-cutter, operating substantially as described.

4. The lip or offset n, formed on the yielding plate F, in combination with the movable shear-blade C³, and arranged to be acted upon by this blade, substantially as described.

5. The set-screw p, and spring o, applied to plates F F', substantially as and for the purposes described.

6. The fixed guide e and yielding pressure-guides f f, arranged and operating in combination with card-cutting mechanism, substantially as described.

7. Spring t, arranged and operating substantially as and for the purpose described.

8. The frictional feed-belt D', or its equivalent, in combination with card-cutting and guiding machinery, constructed and operated substantially as described.

EDWIN COWLES.
